UNITED STATES PATENT OFFICE.

JAMES T. POKORNY, OF PARIS, TEXAS, ASSIGNOR OF ONE-HALF TO A. T. EDDINGSTON,
OF PORT ARTHUR, TEXAS.

BRICK-KILN CONSTRUCTION.

1,386,530.

Specification of Letters Patent.

Patented Aug. 2, 1921.

Application filed March 22, 1918. Serial No. 224,042.

To all whom it may concern:

Be it known that I, JAMES T. POKORNY, a citizen of the United States, residing at Paris, in the county of Lamar and State 5 of Texas, have invented certain new and useful Improvements in a Brick-Kiln Construction, of which the following is a specification.

The invention relates to brick kiln, and 10 more particularly to the class of improvements in kiln construction.

The primary object of the invention is the provision of a kiln construction of this character that bricks as well as tiles may be 15 manufactured, burned and dried under the same roof.

Another object of the invention is the provision of a kiln construction of this character wherein the burning, firing, and drying 20 rooms are arranged in a novel manner and located within a single building adapted for the manufacture, burning and drying of bricks so that a great saving in fuel is accomplished and moreover a considerable re- 25 duction in the time required for the burning of the bricks is obtained and a more uniform and satisfactory product produced. It will be apparent that the use of the heat developed during the burning of the bricks 30 for also effecting the drying of the same is particularly desirable in a brick manufacturing plant and moreover my invention contemplates such an arrangement of this character as is usually efficient for the ends 35 intended.

Further objects of this invention reside in the arrangement of the various flues and fire chamber, in which the bricks are located when being burned to economize on 40 fuel, the particular means being employed for causing the fire to perform the two-fold function of burning the bricks and drying the same is very effective for these purposes.

With these and other objects in view, the invention consists in the features of construction, combination, and arrangement of parts as will be hereinafter fully described, 45 illustrated in the accompanying drawings and pointed out in the claims hereunto appended.

In the accompanying drawings:

Figure 1 is a vertical longitudinal sectional view through a brick kiln construction in accordance with the invention. 50

Fig. 2 is a horizontal sectional view taken on the line 2—2 of Fig. 1.

Fig. 3 is a vertical transverse sectional view on the line 3—3 of Fig. 1.

Similar reference characters indicate corresponding parts throughout the several views in the drawings.

Referring to the drawings in detail, it will be seen that the brick kiln construction comprises a main building 5, which may be 60 of any desirable construction, having at suitable intervals in the side walls thereof doorways 6 to permit access thereto while in the upper portions of these walls are suitable windows 7, for giving light to the interior 65 of the building and also for permitting ventilation when the occasion requires. Located centrally longitudinally within the building 5 is a continuous substantially oval-shaped kiln of any conventional form, 70 having in the outer side thereof suitable doorways 9, so that ingress and egress can be had to the kiln, and within the latter may be stacked the bricks to be fired in the ordinary well-known manner.

Located at suitable distance above the 75 crown of the kiln 8 and extending transversely within the building 5, are superposed floors 10 and 11 respectively for dividing the upper portion of the building into a drying 80 room 12, and a firing room 13, the latter being above the drying room 12, which has located therein a plurality of tracks 14, over any of which is adapted to travel a truck 15, it being understood of course, that any number 85 of trucks are employed and are adapted to carry bricks for the drying thereof, which takes place within the drying room, while the firing room 13 may be utilized for the manufacture of the bricks or tiles. The 90 building 5 is provided with any suitable type of roof 16, while exteriorly of said building is located a vertically disposed smoke stack or chimney 17, which may be of any size and height corresponding to the 95 particular size of the brick kiln plant construction.

Located beneath the floor 10 and disposed horizontally in a longitudinal direction, centrally of the building 5 between the side runs 100 of the kiln 8 is a main flue, 18, which has one end extended exteriorly of the building and in communication with the stack or chimney 17, while the other end of said flue is closed and terminates adjacent to the end wall of 110

the building remote from the stack or chimney 17. Extending upwardly vertically through the floors 10 and 11, from the crown of the kiln 8 at intervals thereof and communicating with said kiln are fuel feeding or conducting pipes 19, which have their upper ends opening into the firing room 13, these upper ends of said pipes being extended only slightly above the floor 11 and 10 have fitted thereon removable caps 20, it being understood that the pipes 19 are arranged in series, of the spaced pipes, transversely of the kiln 8 and on the removal of the cap 20 from any one of the said pipes 19, 15 fuel such as coal or other fuel product can be delivered into said pipe through its upper open end from the firing room 13 and conveyed into the kiln 8 for the charging thereof with fresh fuel, it being understood of course, that any quantity of green fuel can 20 be stored within the firing room 13 in the upper portion of the building 5 of the plant.

Located between the foundation for the building 5 and the bottom of the kiln 8, is 25 a chamber, which may be constructed in any desirable manner, and is of the required width and length and extending through this chamber at intervals beneath the bottom 22 of said kiln 8 are the horizontal elbow portions 23 of draft flues 24, the upstanding vertical portions 25 of which are located centrally relative to the kiln and extend upwardly for communication with the main flue 18, while the horizontal elbow portions 30 35 23 of said flues open laterally as at 26 into the kiln 8 at the outer side thereof. Each vertical portion 25 of the draft flue 24, at its end communicating with the main flue 18, is fitted with a removable damper 27, the same being provided with a lift rod 28, 40 which extends upwardly vertically through the floors 10 and 11, within the firing room 13, where said rod is accessible and can be manually manipulated for the opening and 45 closing of the damper 27 as will be clearly apparent.

On the opening of the draft flues 24, direct draft can be had with the stack or chimney 17 through the main flue 18 and the dampers 27 or said draft flues may be separately 50 operated as desired for the purpose of regulating the draft in the kiln 8 in order to obtain certain particularly efficient results in operating the kiln as will hereinafter appear. 55 It is desirable to have the dampers 27 usually of considerable weight so as to secure the proper closing off of the flues 24 when it is required to regulate the draft in the kiln 8.

60 In the drying room 12, it is understood that each truck 15 is loaded with the green bricks to be dried, the bricks being elevated in any suitable manner into the drying room and loaded upon the trucks either by hand 65 or otherwise.

In the use of the kiln construction, the bricks are stacked upwardly within the kiln, and are placed in such a way as to leave suitable spaces between the stacks of bricks so as to permit the proper circulation of air 70 through the said stacked bricks when the bricks are being fired. The stacked bricks are divided into sections by the use of paper partitions (not shown) as usual. These paper partitions make each divided section airtight and facilitates the firing of the bricks in sections. 75

When starting the fire in the kiln 8, the damper 27 nearest the stack or chimney 17, is open and a light fire started. As soon as the fire gets going, the damper referred to is closed and the next adjacent damper away from the stack or chimney 17 is opened, and this operation is continued throughout the series of dampers and the heat from the kiln 8 and the main flue 18 will rise and pass through rows of openings 29 formed in the floor 10 into the drying room 12 so that the bricks stacked therein will become heated and properly dried. Fuel is delivered to the kiln 8 through the pipes 19 from the firing room 13, above the drying room 12, while the control of the fire within said kiln 8 is effected by manipulating the dampers 27 so that the drying room will become properly 85 heated progressively from one end of the building 5 to the other end thereof. 90

By the time the last sections of the stacked bricks within the drying room 12 have become heated, the first sections of stacked 100 bricks therein have cooled off so that the bricks may be taken out of the same, and a new supply stacked in substitute therefor, but always the same number of bricks are kept ahead of the fire as are being taken out 105 after being burnt behind the fire.

The stacking of the bricks within the drying room 12, and the dividing thereof into sections is accomplished in any ordinary well-known manner. 110

From the foregoing, it is thought that the construction and manner of use of the kiln construction will be clearly understood and therefore a more extended explanation has 115 been omitted.

What is claimed is:

1. In a brick manufacturing plant, a fire chamber, drying and firing chambers arranged in superposed relation above the fire chamber, the floor of the drying chamber having openings therein to admit the heated air circulating about the exterior of the fire chamber, and fuel conducting pipes connecting the firing room with the fire chamber. 120
2. In a brick manufacturing plant, a fire chamber, firing and drying rooms arranged in superposed relation above the fire chamber, and fuel conducting pipes connecting the firing room with the fire chamber and extending through the drying room. 125

3. In a brick manufacturing plant, a fire chamber, superposed brick drying and firing rooms arranged above the fire chamber, fuel conducting pipes connecting the firing room 5 with the fire chamber, and removable caps engaged with the upper terminals of the fuel conducting pipes.
4. In a brick manufacturing plant, a firing chamber, drying and firing rooms arranged 10 in superposed relation above the fire chamber, the floor of the drying room being provided with openings admitting the heated air circulating about the exterior of the fire chamber, fuel conducting pipes connecting the firing room with the fire chamber, and removable caps engaged with the upper terminals of the fuel conducting pipes. 15

In testimony whereof, I affix my signature hereto.

JAMES T. POKORNY.
